SOUND TRANSMITTING VENTILATOR

Jacob M. Goldberg, Denver, Colo.

Application August 5, 1937, Serial No. 157,558

3 Claims. (Cl. 98—96)

This invention relates to improvements in sound transmitting, draft preventing ventilators.

In box offices for moving picture theaters and similar places, the ticket seller is separated from the public by a plate glass partition having an opening through which money can be exchanged for tickets. This opening is of necessity positioned so low that it cannot be used for verbal communication and it is therefore customary to provide a smaller opening in the glass partition at a height convenient for speaking. On cold and windy days, strong drafts will be created through the openings in the partition and the ticket dispensing opening is therefore provided with a readily removable closure. The opening for speech communication is also frequently provided with a pivoted closure that must be moved to open position whenever communication is to be had with a customer.

It is the object of this invention to provide a closure for the speech communication opening which will prevent the formation of drafts and which will permit the transmission of sound waves so that conversation may be carried on between the ticket seller and the customer.

Although this invention will be explained in connection with a ticket booth, it is to be understood that this is merely illustrative of one use and that the invention can be used for other analogous purposes whenever desired.

This invention, briefly described, consists of a readily removable closure for an opening in a partition, formed from two disks, preferably of metal, of somewhat greater dimensions than the opening, the disks are clamped against opposite sides of the partition by means of screws and are both provided with openings so positioned that the openings in one disk are opposed by an imperforate portion of the other disk. The material surrounding the opening is bent inwardly so as to project towards the other disk but is spaced from it so as to provide a tortuous passage that will break up air currents but will permit sound waves to pass.

Having thus briefly described the invention, it will now be described in detail and for this purpose reference will be had to the accompanying drawing in which the invention has been illustrated in its preferred form and in which

Figure 1 is a front elevation of a ticket booth showing the improved ventilator in place therein;

Figure 2 is a front elevation of the ventilator looking inwardly from the outside;

Figure 3 is an elevation looking outwardly from the inside; and

Figure 4 is a section taken on line 4—4 Fig. 2.

In the drawing numeral 5 designates a plate glass partition, but instead of glass it may be of any other suitable material. When the partition forms the wall of a ticket booth, it is provided with an opening 6 positioned directly above the counter 7. At a suitable distance above the counter the partition is provided with a hole 8 that in the example shown is circular, but which may be of any other shape without departing from the invention. Ordinarily the hole 8 is left open in which case a strong draft is produced that makes the occupant of the booth uncomfortable and exposes her to the danger of contracting a cold.

In order to prevent the formation of strong air currents and at the same time permit the sound of the voice to pass through the partition, I have provided a ventilator or closure comprising two disks which have been designated by numerals 9 and 10. In the form illustrated, the disks are circular and are similar in appearance, although not identical. The rim 11 fits against the surface of the plate glass and the two disks are clamped in position by means of screws 12. Each disk has an inwardly extending, circular rib 13 that projects beyond the plane of flange 11 and serves to center the disk in the opening. Disk 9 has an even number of long narrow openings 14 and the material between the openings, which has been designated by numeral 15, is concave on the inner surface and convex on the outer surface. Disk 10 has an odd number of slots 14 separated by concavo-convex portions 15. The slots 14 are so positioned that they are directly across from the solid portions 15 of the other disk and therefore any air currents that flow into the space between the disks will strike the concave surfaces of parts 15 and be deflected so as to follow a path substantially like that shown by arrows 16. Sound waves also enter the slots and pass through to the other side in a manner quite apparent.

It will be seen that due to the staggered arrangement of the slots 14 and the concave surfaces opposed to them, the velocity of the air will be retarded and any air that passes through the ventilator will emerge in a gentle stream of low velocity that will not result in dangerous drafts.

Although the openings 14 have been shown as long, narrow slots, it is apparent from Fig. 4 that round holes may be used, the underlying idea being that the air streams that flow inwardly through an opening 14 will strike a solid wall

15 and be mushroomed so as to cut down their velocity.

By means of this simple device, the occupant of
5 the booth is protected from strong drafts and can
at all times hear what is being said on the other
side of the partition.

This device may be used in doors as well as
partitions, and in any place where sound is to be
transmitted from one side of a wall to another
10 and drafts inhibited.

In the drawing, the disks have been shown circular,
but they may be of any other shape.

The disks are preferably made from metal, but
15 may be made from Bakelite, Celluloid or any similar
product, including glass.

When the disks 9 and 10 are made from metal,
they can be plated and highly polished, and will
add greatly to the ornamental appearance of
20 the booth. In the drawing, the design has been
purposely made as ornamental as is practical,
but instead of the specific appearance shown, any
other design that can be made to fit the situation
can be substituted for the one illustrated.

Having described the invention what is claimed
25 as new is:

1. A sound transmitting ventilator and baffle
for use in an opening in a partition, comprising
30 two disks of somewhat greater dimensions than
the opening and means for clamping the disks
against opposite sides of the partition, each disk
having a plurality of long narrow openings sepa-
35 rated by solid material, the edges of the material
bounding the openings being inclined rear-
wardly terminating adjacent but out of contact
with the solid material between the openings of
the other disk whereby sound waves may freely
pass and air currents passing through the open-
ings will strike the solid material between the
inclined sides and will be constrained to travel

in tortuous paths so as to prevent the formation
of strong drafts.

2. A sound transmitting ventilator and baffle
for use in an opening in a partition, for prevent-
ing drafts and allowing sound waves to pass
5 through the opening, comprising two comple-
mental disks of somewhat larger dimensions than
the opening so that their edges will lap the open-
ing, and means for forcing the disks toward
each other to clamp them in position, each disk
10 having an inwardly extending circular rib for
positioning it in a circular opening and a plu-
rality of parallel spaced slots, the material be-
tween the slots being transversely concave on its
inner surface, the slots on one disk being so po-
15 sitioned that they are opposed by the solid mate-
rial of the other disk, the inwardly inclined edges
of the slots being spaced from the inside surface
of the other disk the inclined walls of the two
disks being substantially parallel and spaced
20 whereby any air currents entering through a slot
will strike the inside surface of the other disk
between two inclined sides.

3. A voice transmitting and draft prevent-
ing ventilator for use in ticket booths and the
like, comprising two spaced disks each having a
plurality of openings surrounded by inwardly in-
clined walls, adjacent walls of adjacent
30 slots forming the sides of a trough, the disks
being so positioned relative to each other that
the openings in one are located opposite a solid
portion of the other, so that air flowing through
the ventilator will enter the openings in one disk,
strike the solid material forming the bottom
35 of a trough of the other disk and spread lat-
erally and rearwardly, whereby its velocity will
be reduced, and finally emerge through the open-
ings in the other disk.

JACOB M. GOLDBERG.
